UNITED STATES PATENT OFFICE.

GUSTAF I. SILBERT AND CARL E. CARLSON, OF CHICAGO, ILLINOIS.

DESIGN FOR A PICTURE-FRAME.

40,877.

Specification for Design.

Patented Sept. 13, 1910.

Application filed July 8, 1910. Serial No. 571,101. Term of patent 7 years.

To all whom it may concern:

Be it known that we, GUSTAF I. SILBERT, a citizen of the United States, and CARL E. CARLSON, a subject of King Gustav of Sweden, both residing at Chicago, in the county of Cook and State of Illinois, have invented a new, original, and ornamental Design for Picture-Frames, of which the following is a specification, reference being had to the accompanying drawing, forming part thereof.

The figure is a face view of a picture frame showing our new design.

We claim:

The ornamental design for a picture frame, as shown.

GUSTAF I. SILBERT.
CARL E. CARLSON.
